UNITED STATES PATENT OFFICE.

LOUIS N. VINCENT, OF SEATTLE, WASHINGTON, ASSIGNOR TO IMPERIAL STEAM APPLIANCE COMPANY, OF SEATTLE, WASHINGTON, A CORPORATION.

AUTOMATIC MEANS FOR DRAINING STEAM ENGINES.

Application filed October 20, 1921. Serial No. 509,127.

To all whom it may concern:

Be it known that I, LOUIS N. VINCENT, a citizen of the United States, residing at Seattle, in the county of King, State of Washington, have invented certain new and useful Improvements in Automatic Means for Draining Steam Engines; and I do declare the following to be a full, clear, and exact description of the invention, such as will enable others skilled in the art to which it pertains to make and use same.

My invention relates to improvements in automatic means for draining engines, and more particularly for draining the steam chest and steam cylinder, etc., of a steam engine of the water of condensation and for draining a multiple of steam chests and steam cylinders of a steam engine or steam engines of the water of condensation.

It is well known that the presence of steam saturated with water, or water of condensation in the steam chest and steam cylinder of a steam engine, reduces very materially its efficiency and often causes the cylinder heads to be blown out, and also that an engine when at rest is frequently started up by a leaky throttle valve, and the object of my invention is to correct or obviate these faults by providing means for draining, exhausting or eliminating from the steam chest and steam cylinder of an engine, or a multiple of steam chests and steam cylinders of a steam engine or steam engines, all the water of condensation which may collect therein, due either to the leakage of the throttle valve or other steam inlet valve or other cause, and at the same time prevent the water of condensation from returning to the steam chest or cylinder after being drained or exhausted therefrom.

A further object is to provide means for exhausting or draining engines, and more particularly draining the water of condensation from a steam chest and cylinder of a steam engine and from a multiple of steam chests or cylinders of a steam engine or steam engines simultaneously by means of a by-pass and to cause the same to be exhausted.

50 A further object is to provide means having a minimum number of parts and which is simple, inexpensive and durable in construction and effective and easy in operation.

The invention consists in the several features and in the construction, combination

and arrangement of such features as more fully hereinafter described and claimed.

Referring to the drawings:

Fig. 1 is a central vertical sectional view taken through the cylinder and steam chest 60 of a steam engine, some of the parts being shown in elevation.

Fig. 2 is a diagrammatic view, showing my invention as it appears when draining a multiple of steam engine cylinders and 65 steam chests.

Fig. 3 is a sectional view of the exhaust valve.

In the drawings, in which similar reference characters denote similar parts throughout the several views, 1 represents the piston or steam cylinder of a steam engine of well known type provided with a piston 2 having a piston rod 3, packing 4, combined steam inlet and outlet passages 5, 5', steam exhaust or outlet passage 6, outlet passages 6', 6² for the exhaust of water of condensation, a steam chest 7 having a D slide valve 8 with cavity 8' and operating rod 9, steam inlet pipe 10 provided with a throttle or steam inlet valve 11, vertical pipes 12 and 13 connected at their upper ends 14, respectively, with the water outlet passages 6', 6² and their lower ends with a horizontal main drain pipe 15, and intermediate their ends 75 the vertical pipes 12 and 13 each provided with a normally open gravity valve 16 closed automatically by means of the back pressure of the steam from the steam chest through pipe 17 and pipes 15, 12 and 13, these valves 80 controlling the exhaust of water of condensation from the cylinder into an exhaust pipe.

A vertical pipe 17 is provided for the steam chest 7, the upper end connected to 95 and communicating with the steam chest 7 at 18 and the lower end connected to and communicating with the horizontal pipe 15 at 19.

A vertical pipe 20 is connected to pipe 15 at point 21 and is provided with a normally open valve 22 having a spring 23 for keeping it normally open. This valve 22 allows the exhaust water of condensation to pass through the same to the exhaust pipe 25, 100 but is closed automatically by means of the back pressure of the steam.

It will be noted that this single valve 22 is capable of performing its functions equally as well with a multiple of steam chests and 110

cylinders, see Fig. 2, as with a single steam chest and cylinder, see Fig. 1.

A vertical by-pass pipe 24 is connected to the horizontal pipe 15 at the upper end and 5 at the lower end is connected to and communicates with the exhaust pipe 25 below the valve 22, and 26 is a by-pass hand valve which, when opened sufficiently, reduces the back pressure of the steam against the water 10 exhaust valves 16, the valve 22 thus permitting them to open and drain the cylinder while the engine is working and the steam pressure is on.

By the use of the drain pipe 17 the condensed steam or water of condensation is 15 drained directly from the steam chest 7 without being allowed to pass into the piston cylinder and by use of the valves 16, 16 and valve 22, by-pass 24 and hand valve 20 26 the condensed steam or water of condensation is drained from the piston cylinder, this latter being for the reason that the steam passes through pipe 17 from the steam chest into pipes 15, 12, 13 and 20 25 and the back pressure thereof on the valves 22, 16 and 16 closes them and the exhaust of steam through the by-pass 24, when its pressure against valves 16, 16 and 22 is reduced by opening the hand valve 26, causes 30 the valves 16, 16 and 22 to open and the water of condensation passes from the piston cylinder through valves 16, 16, pipes 12 and 13, by-pass 24 and out through the exhaust pipe 25 below valve 22.

35 The back pressure in the pipe 15 of the steam from the chest 7, and also from the piston cylinder, forces valves 16, 16 onto their seats and holds them there until the engine throttle is closed. It very often happens when the engine is priming or being 40 started up after standing a while and getting cold that the cylinders condense and accumulate a quantity of water, even while the pressure of steam is on, which is very 45 dangerous and frequently results in the blowing out of the cylinder heads by the pressure of the piston against the accumulated water, and, in order to obviate or correct this condition, I use the by-pass 24 and 50 its hand valve 26 as hereinbefore described.

By opening the hand valve 26 partially or 55 fully the back pressure in the pipes 15, 12 and 13 is proportionately reduced, allowing the valves 16, 16 and 22 to open slightly or fully, as required, and causing some of the steam to pass through valve 26, the by-pass 24, around valve 22 and out through the exhaust pipe 25, thus draining out all the surplus water from the cylinder.

60 Another important use for which the by-pass and valve 26 are used is that it sometimes happens that a locomotive is at rest in a roundhouse with the throttle closed and the engineer leaves for the night that 65 the throttle valve will leak and steam will

escape from the boiler through the leaky throttle valve into the steam chest and pass from thence through the pipes leading to the valve 22, causing said valve to become seated and causing a back pressure to accumulate and close the valves 16, 16 and prevent the water from being drained automatically out of the cylinder and steam chest.

To prevent such a condition all the 70 engineer has to do is to reduce the back pressure by opening the hand valve 26 and the water will drain off as hereinbefore described.

In starting a locomotive by means of the 80 pressure of the steam resulting from a leaky throttle the engineer may by leaving the hand valve 26 open before he quits cause the accumulated pressure of the steam leaking through the throttle to pass through 85 the hand valve 26 and out through the by-pass 24 to the exhaust pipe 25 as fast as it accumulates, thus preventing the steam from acquiring sufficient pressure to start the engine while the engineer is absent. 90

The operation is as follows:

The engine being in operation and the piston being in the position shown, there is spent steam to its right and live steam is entering the steam chest 7 from the boiler 95 through pipe 10, and as the D slide valve 8 moves to the right the passage 5 is uncovered, admitting the live steam on the left of the piston 2 and at the same time the cavity 8' therein establishes communication 100 between the passage 5' and outlet passage 6, whereupon live steam will force the piston to the right and the spent steam will be exhausted from the cylinder through the passage 5' and out through the outlet 105 passage 6. When the D slide valve moves to the left the passage 5' is uncovered, admitting the live steam on the right of the piston 2 and at the same time the cavity 8' therein establishes communication 110 between the passage 5 and the outlet passage 6, whereupon live steam will force the piston to the left and the spent steam will be exhausted from the cylinder through the passage 5 and out through the outlet passage 6. At the same time that the live steam enters the passages 5, 5' it passes alternately from the steam chest through pipe 17 into pipes 15, 20 and pipes 12 and 13, closing the valve 22 against the action 115 of the spring 23 and closing the valves 16, 16, whereupon, the hand valve 26 being opened, partially or fully as desired, part or all of the steam will accordingly pass from pipes 15, 20, 12 and 13 through the 120 by-pass 24 and out of the exhaust pipe 25 below the valve 22, relieving the pressure upon the valves 16, 16 and 20 partially or entirely and allowing them to open accordingly partially or entirely, and the water 125 130

of condensation will exhaust from the cylinder into and through the exhaust pipe and the water of condensation will be exhausted from the steam chest through pipe 5 17 into pipe 15 and therefrom through the valve 22 into and out of exhaust pipe 25.

I do not wish to be understood as limiting myself to the specific details of construction and arrangement as herein described 10 and illustrated, as it is manifest that variations and modifications may be made in the features of construction and arrangement in the adaptation of the device to the various conditions of use without departing 15 from the spirit and scope of my invention and improvement.

What I claim is:

1. In a device for draining the water of condensation from steam engines, a steam 20 chest, a steam cylinder, normally open valves for draining the water of condensation from the cylinder adapted to be closed by back pressure of steam, means for reducing the back pressure of the steam 25 against said normally open valves and allowing them to open and drain the water of condensation from the cylinder, and means for draining the steam chest.

2. In a device for draining the water of 30 condensation from steam engines, a steam chest, a steam cylinder, normally open valves for draining the water of condensation from the cylinder, means for causing back pressure of steam against said normally open 35 valves to close the same, and means for reducing the back pressure of steam against said valves and allowing them to open and drain the water of condensation from the cylinder.

3. In a device for draining the water of condensation from steam engines, a steam chest, a steam cylinder, normally open valves for draining the water of condensation from the cylinder, means for causing back pressure 45 of steam against said normally open valves to close the same, means for reducing the back pressure of steam against said valves and allowing them to open and drain the water of condensation from the cylinder, and 50 means for draining the steam chest.

4. In a device for draining the water of condensation from steam engines, a steam chest, a steam cylinder, normally open valves for draining the water of condensation from the cylinder adapted to be closed by back pressure of steam, and a by-pass for reducing the back pressure of the steam 55 against said normally open valves and allowing them to open and drain the water of condensation from the cylinder.

5. In a device for draining the water of condensation from steam engines, a steam chest, a steam cylinder, normally open valves for draining the water of condensation 60 from the cylinder adapted to be closed

by back pressure of steam, a by-pass for reducing the back pressure of the steam against said normally open valves and allowing them to open and drain the water of condensation from the cylinder, and means 70 for draining the steam chest.

6. In a device for draining the water of condensation from steam engines, a steam chest, a steam cylinder, normally open valves for draining the water of condensation from the cylinder, means for causing back pressure of steam against said normally open valves to close the same, and a by-pass for reducing the back pressure of steam against said normally open valves and 80 allowing them to open and drain the water of condensation from the cylinder.

7. In a device for draining the water of condensation from steam engines, a steam chest, a steam cylinder, normally open 85 valves for draining the water of condensation from the cylinder, means for causing back pressure of steam against said normally open valves to close the same, a by-pass for reducing the back pressure of steam 90 against said normally open valves and allowing them to open and drain the water of condensation from the cylinder, and means for draining the steam chest.

8. In a device for draining the water of 95 condensation from steam engines, a steam chest, a steam cylinder, valves controlling the exhausting of water of condensation from the cylinder closed by steam pressure, and means for reducing said steam pressure to 100 allow said valves to open and exhaust the water of condensation from the steam cylinder.

9. In a device for draining the water of condensation from steam engines, a steam 105 chest, a steam cylinder, valves controlling the exhausting of water of condensation from the cylinder closed by steam pressure, means for reducing said steam pressure to allow 110 said valves to open and exhaust the water of condensation from the steam cylinder, and means for exhausting the water of condensation from the steam chest.

10. In a device for draining the water of condensation from steam engines, a steam 115 chest, a steam cylinder, valves controlling the exhausting of water of condensation from the cylinder closed by steam pressure, and a by-pass for reducing said steam pressure to allow said valves to open and exhaust 120 the water of condensation from the steam cylinder.

11. In a device for draining the water of condensation from steam engines, a steam chest, a steam cylinder, valves controlling the 125 exhausting of water of condensation from the cylinder closed by steam pressure, a by-pass for reducing said steam pressure to allow said valves to open and exhaust the water of condensation from the steam cylinder. 130

- der, and means for exhausting the water of condensation from the steam chest.
12. In a device for draining the water of condensation from steam engines, outlet pipes with normally open valves connected to the water outlets of a steam cylinder, a connecting pipe forming a communication between said outlet pipes, a pipe connected to a steam chest at one end and the opposite end to the said connecting pipe, an exhaust pipe connected to said connecting pipe and provided with a normally open valve, a by-pass connected to said connecting pipe and the exhaust pipe forming a communication with said exhaust pipe around the valve in the exhaust pipe.
13. In a device for draining the water of condensation from steam engines, a steam cylinder and steam chest, water outlet pipes, with valves, connected to the water outlets of the cylinder, a pipe connecting said outlet pipes, a pipe connected to the steam chest at one end and the connecting pipe at the other end, an exhaust pipe connected to said connecting pipe and provided with a valve, a by-pass connected to said connecting pipe and the exhaust pipe forming a communication with said exhaust pipe and connecting pipe around the valve in the exhaust pipe.
14. In a device for draining the water of condensation from steam engines, a drain pipe, a supplementary drain pipe connected to the first mentioned drain pipe and the steam chest, an exhaust pipe, and means forming a communication between said supplementary drain pipe and the exhaust pipe.
15. In a device for draining the water of condensation from steam engines, a main drain pipe connecting the water outlets from the steam cylinder and provided with an exhaust pipe having a valve, valves for said outlets, a supplementary drain pipe communicating with the main drain pipe and the steam chest, and a by-pass pipe connected with the main drain pipe and exhaust pipe.
16. In a device for draining the water of condensation from steam engines, a drain pipe having drain valves adapted to be closed by back pressure of steam, and means for reducing the back pressure of steam in said drain pipe and causing said drain valves to open.
17. In a device for draining the water of condensation from steam engines, a steam chest, a piston cylinder communicating therewith, drain pipes connected to said piston cylinder each having a drain valve, a drain pipe connected to the steam chest, a main drain pipe connecting the drain pipes of the piston cylinder and the drain pipe of the steam chest, an exhaust pipe and valve therefor, and means for reducing back pressure of steam in the drain pipes, thereby allowing the said drain valves to open and drain the steam chest and piston cylinder.
18. In an engine, a motive fluid supply, a motive fluid cylinder, means controlling the exhaust of condensation from said cylinder, means operated by motive fluid from said supply to close said exhaust controlling means and means for reducing the pressure of motive fluid against said exhaust controlling means, to allow said exhaust controlling means to open and exhaust the condensation from said cylinder.
19. In an engine, a motive fluid supply, a motive fluid cylinder, means controlling the exhaust of condensation from said cylinder, means operated by motive fluid from said supply to close said exhaust controlling means and means for reducing the pressure of motive fluid against said exhaust controlling means, to allow said exhaust controlling means to open and exhaust the condensation from said cylinder, and means for exhausting the condensation from said motive fluid supply.
20. In an engine, a motive fluid supply, a motive fluid cylinder, means controlling the exhaust of condensation from said cylinder, means operated by motive fluid from said supply to close said exhaust controlling means and a by-pass for reducing the pressure of motive fluid against said exhaust controlling means to allow said exhaust controlling means to exhaust the condensation from said cylinder.
21. In an engine, a motive fluid supply, a motive fluid cylinder, means controlling the exhaust of condensation from said cylinder, means operated by motive fluid from said supply to close said exhaust controlling means and a by-pass for reducing the pressure of motive fluid against said exhaust controlling means to allow said exhaust controlling means to exhaust the condensation from said cylinder, and means for exhausting the condensation from motive fluid supply.

In testimony whereof I have affixed my signature.

LOUIS N. VINCENT.
